UNITED STATES PATENT OFFICE.

GEORGE G. PREFANTAINE, OF WHITEHALL, NEW YORK, ASSIGNOR OF
ONE-HALF TO CHARLES C. WETMORE, OF SAME PLACE.

OIL-CUP.

SPECIFICATION forming part of Letters Patent No. 390,986, dated October 9, 1888.

Application filed March 16, 1888. Serial No. 267,363. (Model.)

To all whom it may concern:

Be it known that I, GEORGE G. PREFANTAINE, a citizen of the United States, and a resident of Whitehall, in the county of Washington and State of New York, have invented certain new and useful Improvements in Oil-Cups; and I do hereby declare that the following is a full, clear, and exact description of the invention, which will enable others skilled in the art to which it appertains to make and use the same, reference being had to the accompanying drawings, which form a part of this specification, and in which—

Figure 1 is a central vertical sectional view of my improved oil-cup, showing the parts within the same in side view. Fig. 2 is a central vertical sectional view of the cup and of all the parts within it. Fig. 3 is a similar view of the lower portion of the cup with the parts 20 in the opposite position from that shown in Fig. 2.

The same numerals of reference indicate the same or corresponding parts in all the figures.

My invention has relation to that class of oil-cups for lubricating the cylinders, valve-chests, or similar parts of engines, pumps, and similar machinery, in which the pressure of the fluid in the cylinder to be lubricated will 30 close a valve, which will open another valve, admitting a quantity of the lubricant above the first valve, which will pass out of the cup when the valve is opened by the release of the pressure in the cylinder, the cup thus feeding the lubricant by the alternating pressure and 35 release of the fluid generating the motion in the engine to be lubricated; and it consists in the improved construction and combination of parts of such an oil-cup, as hereinafter more 40 fully described and claimed.

In the accompanying drawings, the numeral 1 indicates a cylindrical casing, which is preferably formed with vertical slots 2, through which an inner cylinder, 3, of glass is visible, 45 these slots and the inner cylinder enabling the contents of the oil-cup to be inspected.

The top of the cup is formed with a central screw-threaded aperture, 4, in which a screw-threaded cap or stopper, 5, having a handle, 6, fits, and through which aperture the cup 50 may be filled.

The bottom of the cylinder is formed with a central aperture, 7, in which is screwed a nipple, 8, having an axial chamber, 9, contracted at its upper and lower ends, and formed with 55 an upwardly-facing valve seat, 10, at the upper end, slightly above the bottom of the cylinder, and with a downwardly-facing lower valve-seat, 11, a distance from the lower end, the lower portion, 12, of the nipple 8, below 60 the lower valve-seat, being reduced, and having perforations 13 in the sides.

A nozzle, 14, is screwed with its upper end upon an external screw-thread, 15, upon the lower reduced portion of the nipple 8, and is 65 formed with a flat seat, 16, in its lower end, the discharge channel or aperture 17 opening through this seat.

A valve, 18, may rest with its flat and grooved or notched lower face upon the seat 70 16, and may fit with its conical upper side upon the downwardly-facing valve-seat 11, and the stem 19 is formed with an enlargement, 33, above the valve, which fits in the lower contraction in the bore of the nipple, 75 34 and is provided with longitudinal grooves 34.

Near the upper end of the stem 19 an adjustable collar, 20, is secured, against which the lower edge of a hollow lower stem, 21, of a 80 valve, 22, may rest, the said collar gaging the downward play of the valve.

A cap, 24, is secured upon the upper end of the nipple 8, and is provided with a tubular extension, 25. Longitudinal slots 26 are 85 formed at the base of this extension, which are opened or closed by means of the adjustable collars 27, that are secured upon the exterior of the extension. The top of the cap 24 is provided with a valve-seat, 28, against which the 90 upper face of the valve 22 bears when it is raised by the pressure of the motive fluid upon the lower end of the valve 18. A circumferential groove, 29, is formed around the stem 21 where it joins the valve 22, from which 95 groove perforations 30 lead into the interior of the stem. The exterior of this stem of the valve 22 is provided with grooves 28, while the stem 31 upon the upper portion of the valve, which fits within the hollow of the extension 25, is provided with grooves 32.

In operation the nozzle 14 of the oil-cup is

screwed into a suitable aperture in the cylinder, valve-chest, or other machine part to be lubricated, and the glass cylinder 3 filled with oil and the size of the apertures 26 26 properly 5 adjusted by means of the collars 27. The oil then passes through the apertures 26 into the interior of the cap 24, but is prevented from going farther by reason of the valve 22. When the machine is in motion, the motive fluid enters 10 the cup through the aperture 17 in the nozzle 14, and bears against the lower end of the valve 18 and lifts it from its seat. As the valve 18 is thus lifted up, the collar 20 upon the stem 19 is brought against the lower end 15 of the hollow stem 21 and lifts the valve 22 from its seat and raises it up until the upper face of the valve bears against the valve-seat 23 and prevents any more oil from entering the cap 24, and also prevents the steam from escaping 20 into the glass cylinder 3. As soon as the valve 22 is raised from the seat 10, the oil passes from the interior of the cap 24 down into the chamber 9 of the nipple 8, from whence it passes through the channels 34 of the valve- 25 stem 19 down into the lower portion of the nipple, where it is stopped by the upper face of the valve 18 bearing against the valve-seat 11. When the exhaust takes place, the valve 18 drops to its lowest point, and with it the valve 22, which thus closes the passage between the interior of the cap 24 and the chamber 9, and prevents the passage of more oil until the valve is again raised by the admission 30 of motive fluid to the lower portion of the valve 18. At the same time that the passage between the interior of the cap 24 and the chamber 9 is closed the passage between the cylinder 3 and the interior of the cap is open, and a fresh supply of oil is admitted to the interior 35 of the cap 24. During the exhaust of each stroke the oil which has thus slowly worked its way to the lower portion of the oil-cup as the valves 18 and 22 have alternately been opened and closed, as before described, 40 is drawn down through the aperture 17 to the portion of the machine which is to be lubricated.

The lubricant will pass out into the nozzle through the perforations in the lower contracted end of the nipple, and the motive fluid, which has entered the chamber in the nipple through the axial bore of the valve and stem, will assist in forcing the lubricant out of the chamber and into the cylinder.

The supply of lubricant may be governed by adjusting the collars upon the tubular extension, to cover more or less of the slots in the same, and by adjusting the collar upon the stem of the lower valve this collar governs 55 the upward rise of the upper valve and consequently the flow of lubricant passing through the valve-seat of this valve.

In addition to the elements described above, I prefer to use an auxiliary valve, 35, which 60 is secured in a recess, 36, in the upper end of the stem 19 by means of a cap, 37, the stem 19 being provided with a longitudinal bore,

38, and the cap being provided with an aperture, 39. In operation, when the motive fluid enters the nozzle 14, it passes up through the bore 38 and lifts the auxiliary valve until its upper end closes the aperture 39 and prevents the fluid from passing out of the cap. As soon as the exhaust takes place, the auxiliary valve falls, and the lubricant, which has passed 70 into the interior of the stem 21, enters the aperture 39 and passes down the sides of the auxiliary valve, where it remains until the valve is again raised, when the lubricant passes 75 into and down through the bore 38 of the stem 19.

Having thus described my invention, I claim and desire to secure by Letters Patent of the United States—

1. In an oil-cup, the combination, with a 85 nipple in the cup or cylindrical casing, having an upwardly and a downwardly facing valve-seat in its upper and lower ends, respectively, a valve playing upon the lower valve-seat and having an upwardly-projecting stem, and a 90 double valve upon the upper seat having a hollow downwardly-projecting stem and a grooved upwardly-projecting stem, of a cap 95 over the upper valve-seat and valve, and formed with an upward tubular extension having longitudinal slots in its lower portion, and adjustable collars upon its lower portion, and formed with a downwardly-facing valve-seat at the foot of the extension, as shown, and for the purpose specified. 100

2. In an oil-cup, the combination, with a nipple in the bottom of the cup having an upwardly-facing valve-seat at the upper end and a downwardly-facing seat at the lower end, of a valve playing upon the lower seat and having an upwardly-projecting stem formed with an adjustable collar, and a valve upon the upper seat having a tubular downwardly-extending stem having its end bearing against the collar, as shown, and for the purpose 105 specified.

3. In an oil-cup, the combination of the cylindrical casing, the nipple having the valve-seats 10 and 11, and the perforated and reduced lower portion, 12, the nozzle having 115 the flat seat 16 and aperture 17, the lower valve having the stem formed with the axial bore and with the grooved enlargement and provided with the adjustable collar, the upper valve having the lower tubular stem formed 120 with longitudinal grooves and with the circumferential groove and with the perforations through it, and having the longitudinally-grooved upper stem, and the cap having the tubular extension formed with the slots and 125 with the adjustable collars, as shown, and for the purpose specified.

In testimony that I claim the foregoing as my own I have hereunto affixed my signature in presence of two witnesses.

GEORGE G. PREFANTAINE.
